UNITED STATES PATENT OFFICE

ROBERT J. HODGE, OF WEST HAVEN, CONNECTICUT, ASSIGNOR TO AMERICAN BUCKLE COMPANY, OF WEST HAVEN, CONNECTICUT, A CORPORATION

SLIDE BUCKLE

Application filed June 22, 1931. Serial No. 545,996.

My invention relates to an improvement in slide-buckles and particularly to buckles which are especially adapted for use on overalls-suspenders, the object being to produce a slide-buckle of the class described, which shall be of superior resistance to the strains imposed upon it tending to bend and deform its intermediate- and upper- and lower-bars, especially the former.

10 In the accompanying drawings:

Fig. 1 is a face view of a slide-buckle constructed in accordance with my invention;

Fig. 2 is a plan view thereof;

15 Fig. 3 is a sectional view on the line 3—3 of Fig. 1;

Fig. 4 is a sectional view on the line 4—4 of Fig. 1;

Fig. 5 is a sectional view on the line 5—5 of Fig. 1; and

20 Fig. 6 is a face view of one of the modified forms which my improved buckle may assume.

In carrying out my invention as herein shown, I employ a buckle-frame formed 25 from a single strip of wire bent into rectangular shape to form an upper-bar 10, a lower-bar 11, and complementary end-bars 12 and 13. Preferably, the ends of the wire meet in the middle of the lower-bar 11 and are 30 there united by electric welding at the point 14. The intermediate-bar 15, which may or may not slide upon the end-bars 12 and 13, is formed at its ends with complementary 35 eyes 16 clasping the end-bars, on which they preferably slide up and down. If desired, however, the ends of the intermediate-bar may be fixed to the end-bars so as not to slide thereupon, and it may be undulating in form, as shown, or left straight, as desired.

40 For the purpose of stiffening the intermediate- or slide-bar 15 against the severe downward strains imposed upon it when in use by the buckle-strap, it is swaged so as to produce continuous, central, longitudinal 45 stiffening-ribs 17 and 18 located opposite each other in the plane of the frame, as shown in Fig. 4 of the drawings. These ribs greatly stiffen the bar and prevent it from yielding and bending and so deforming under 50 the severe strains imposed upon it by the

suspender-strap. As shown, these ribs 17 and 18 are flanked by corrugations 19, whereby its gripping power is heightened.

Also, for the purpose of stiffening the upper- and lower-bars 10 and 11 of the buckle-frame, they may, if desired, be correspondingly swaged so as to produce stiffening-ribs 20 and 21 upon their upper and lower surfaces, in addition to corrugating, and so roughening them, as at 22.

As shown in Fig. 1, the upper- and lower-bars are flattened in the plane of the frame on both sides of their centers, but in the modified form shown in Fig. 6 the upper-bar of the buckle-frame also has its central portion flattened in the manner described, its lower-bar being flattened on opposite sides of its central portion, which is welded as at 14.

I claim:

1. In a slide-buckle, the combination with a frame having parallel upper- and lower-bars and end-bars, of an intermediate-bar mounted upon the said end-bars and swaged to produce a continuous central longitudinal stiffening-ribs located upon its respective upper and lower faces and flanked upon its edges by corrugations for preventing the strap from slipping, whereby the bar is stiffened against strain in the plane of the buckle-frame.

2. In a slide-buckle, the combination with a frame having parallel upper- and lower-bars and end-bars, of an intermediate-bar mounted upon the said end-bars and swaged to produce a continuous central longitudinal stiffening-rib upon its upper and lower faces, whereby it is stiffened against strains in the plane of the frame.

3. In a slide-buckle, the combination with a frame made from a single piece of wire bent to form a rectangular frame having upper- and lower-bars and end-bars, of an intermediate-bar mounted upon the end-bars so as to slide thereupon and swaged to produce a continuous central longitudinal stiffening-rib located upon its respective upper and lower faces and flanked along its edges by corrugations, whereby the bar is stiffened against strains in the plane of the frame and

adapted to prevent the strap from slipping.

4. In a slide-buckle, the combination with a frame made from a single piece of wire bent to form a rectangular frame having upper- and lower-bars and end-bars, of an intermediate-bar installed between the said end-bars, so as to slide thereupon, and swaged to produce continuous central longitudinal stiffening-ribs flanked on either side by roughened surfaces.

In testimony whereof, I have signed this specification.

ROBERT J. HODGE.
